UNITED STATES PATENT OFFICE.

THOMAS A. JEBB AND WILLIAM T. JEBB, OF BUFFALO, NEW YORK.

STARCH-TABLE.

SPECIFICATION forming part of Letters Patent No. 256,221, dated April 11, 1882.

Application filed January 20, 1881. (No model.)

To all whom it may concern:

Be it known that we, THOMAS A. JEBB and WILLIAM T. JEBB, of the city of Buffalo, in the county of Erie, in the State of New York, 5 have invented new and useful Improvements in Starch-Tables, of which the following is a specification, reference being had to the accompanying drawings.

This invention relates more particularly to 10 that class of starch-separators which consist of shallow trays, pans, or tables, and which are employed for the purpose of separating the starch from the gluten and other deleterious substances. These starch separators or 15 tables are of great length, frequently exceeding a hundred feet, and they are required to stand at a slight inclination to permit an even flow of the liquid over the same from end to end, in order to effect the desired separation. 20 The position of these tables changes from numerous causes, more especially the settling of the supports and the warping of the material from which the tables and the supports are constructed. A deviation from the true position 25 of the tables results immediately in an uneven flow of the liquid, and consequently in an imperfect separation and corresponding waste of starch.

The object of our invention is to provide a ready means for the adjustment of these tables; and it consists of the particular construction of the mechanism whereby the tables are adjusted, as will be hereinafter fully set forth.

In the accompanying drawings, Figure 1 is a cross-section of a set of starch-tables provided with our improvements. Fig. 2 is an elevation, on an enlarged scale, of the means for adjusting the tables. Fig. 3 is an elevation 40 at right angles to Fig. 2. Fig. 4 is a top plan view of the adjusting mechanism.

Like letters of reference refer to like parts in the several figures.

A represents one or more starch-tables of 45 the usual construction. Three or four of these starch-tables are preferably arranged side by side and supported upon cross-sills B by stringers C. The cross-sills B are arranged between

each pair of posts D, and constructed preferably of iron.

E represents a shoe, preferably made of cast-iron, and secured to each end of each cross-sill B by bolts or other suitable means. The shoes E are provided on their under side with an inclined face, e, and F is a wedge which 55 bears with its inclined upper surface, f, against the correspondingly-inclined lower face of the shoe E. The wedge F slides on a horizontal keyway, G, which is secured to the beam H, and the wedge is actuated by a screw, i, working in a threaded lug, I, cast on the keyway G. The shoe E is guided vertically between two plates, J, which are secured to the post D, and which prevent the sills B and the tables resting thereon from moving lengthwise under the 60 influence of the wedges, while permitting of the desired vertical movement of the shoes and the sills and tables connected therewith. The keyway G is provided on its upper side with a longitudinal rib, l, fitting in a groove, 65 m, on the under side of the wedge F, and the latter is provided on its upper side with a rib, n, fitting in a groove, o, in the under side of the shoe, whereby the shoe, wedge, and keyway are retained in the proper relative position.

By moving the wedge F in one or the other direction the end of the sill resting thereon is raised or lowered, and the portion of the table which is supported on the sill is correspondingly adjusted.

The adjusting devices are in convenient reach of the men who work on the starch-tables, and are readily operated by applying a suitable wrench to the screws by which the 85 wedges are moved.

We claim as our invention—

1. The combination, with a starch-table, of wedges F, resting on supports or ways G and engaging under plates or shoes E, and guides 90 whereby the parts resting on the wedges are held against lateral displacement, but permitted to move vertically, substantially as set forth.

2. The combination, with a starch-table, of 95 wedges F, resting on supports or ways G and

engaging under plates or shoes E, guides whereby the parts resting on the wedges are held against lateral displacement, but permitted to move vertically, and screws where-
5 by the wedges are adjusted, substantially as set forth.

3. The combination, with one or more starch-tables, of cross-sills B, provided with shoes E, wedges F, horizontal ways G, secured to

the beams H, and vertical guides J, between to which the shoes E slide, substantially as set forth.

THOMAS A. JEBB.
WILLIAM T. JEBB.
